(Cl. D26—5)

To all whom it may concern:

Be it known that we, Vera C. Hodges and Thomas B. Smallwood, citizens of the United States, residing in the city of Los Angeles and the city of Burbank, respectively, both in the county of Los Angeles and State of California, have invented a new, original, and ornamental Design for Engine Starter Housing, of which the following is a specification, reference being had to the accompanying drawing, forming part thereof.

Fig. 1 is a perspective view of an engine starter housing showing our new invention.

Fig. 2 is an end elevational view.

Fig. 3 is an elevational view, looking in the opposite direction to Fig. 2.

Fig. 4 is a side elevational view.

We claim:

The ornamental design for an engine starter housing, substantially as shown.

VERA C. HODGES.
THOMAS B. SMALLWOOD.
